(57) **CLAIM**

The ornamental design for a display screen with transitional graphical user interface, as shown and described.

DESCRIPTION

FIG. 1 is a front view of the first image in a sequence of a display screen with transitional graphical user interface, according to a first embodiment of the new design;

FIG. 2 is a top view thereof;

FIG. 3 is a bottom view thereof;

FIG. 4 is a left side view thereof;

FIG. 5 is a right side view thereof;

FIG. 6 is a rear view thereof;

FIG. 7 is a second image thereof;

FIG. 8 is a third image thereof;

FIG. 9 is a front view of the first image in a sequence of a display screen with transitional graphical user interface, according to a second embodiment of the new design;

FIG. 10 is a top view thereof;

FIG. 11 is a bottom view thereof;

FIG. 12 is a left side view thereof;

FIG. 13 is a right side view thereof;

FIG. 14 is a rear view thereof;

FIG. 15 is a second image thereof; and,

FIG. 16 is a third image thereof.

The appearance of the transitional image sequentially transitions between the images shown in FIGS. 1, 7, and 8. The appearance of the transitional image sequentially transitions between the images shown in FIGS. 9, 15, and 16. The process or period in which one image changes state to another image forms no part of the claimed design.

The outermost solid line rectangle depicts the display screen. The broken lines showing an electronic device illustrate environmental subject matter, whereas the broken lines showing elements of the graphical user interface illustrate portions of the article. None of the broken lines form part of the claimed design.
